FLEXIBLE APRON LOOP DRIER

Philip W. Bur, Philadelphia, Pa., assignor to
Proctor & Schwartz, Incorporated, Philadelphia, Pa., a corporation of Pennsylvania

Application May 15, 1930. Serial No. 452,725

9 Claims. (Cl. 34—12)

This invention relates to apparatus for drying or otherwise treating plastic materials such as paints, pigments, chemicals, etc.

The apparatus in general is somewhat similar to the apparatus shown and described in the co-pending application of Alpheus O. Hurxthal, Serial No. 370,662, filed June 13, 1929, which has matured into Patent No. 1,777,972 involving the use of an endless foraminous conveyer 10 of the general character disclosed in the said Hurxthal application, with the exception the conveyer apron in the present case is provided with girts of the nature shown and described in my co-pending application, Serial No. 370,911, filed June 14, 1929, which has matured into Patent 15 No. 1,891,140.

In each of the above mentioned applications the material to be treated is pressed into the endless conveyer apron while the said apron is being moved in a substantially horizontal plane, 20 the conveyer passing around a suitable roller, after having been loaded with the material to be treated, which changes the direction of movement of the apron from the horizontal plane in- 25 to a substantially vertical plane.

Adjacent the top of the apparatus the conveyer apron passes around a second roller and is fed downwardly thereby between a pair of spaced parallel movable supports, which are disposed respectively at the opposite sides of the apron and adapted to be engaged by the ends of the apron girts, which extend beyond the longitudinal side edges of the apron, the movable supports moving in a horizontal plane at a pre- 35 determined rate of speed relative to the speed at which the apron is fed between the said movable supports, whereby the apron is formed into a series of loops suspended by the girts from the said movable supports disposed at opposite sides 40 of the apron.

From the above, it will be noted that the apron, after receiving the material to be treated, is subjected to flexing or bending first in one direction through an angle of substantially 90° and then through an angle of substantially 180° in an opposite direction to the first bending, after which the apron is subjected to still another bending of substantially 180° starting at 45 one girt, when it engages the movable supports, and progressing through the section of the apron disposed between the last girt deposited on the movable supports and the next successive girt, while the said section of the apron is being 50 formed into a loop which is completed when the

last said girt is deposited on the movable supports.

The object of the present invention is to eliminate this multiplicity of flexings of the apron, which, with some kinds of material, has a tendency to loosen the material in the belt to such an extent that the material will fall therefrom.

According to the principles of my present invention, the portion of the apron disposed between any two of the girts is subjected to but one flexing, which takes place at a point substantially equidistant from each of any two successively positioned girts. This single flexing is produced in such a gentle, easy manner that the tendency to loosen the material is reduced to a minimum, or is entirely eliminated.

In the accompanying drawings:

Fig. 1 is a diagrammatic longitudinal sectional elevation of an apparatus embodying the principles of my present invention;

Fig. 2 is a sectional plan view taken on the line 2—2, Fig. 1;

Fig. 3 is a transverse sectional elevation taken on the line 3—3, Fig. 1;

Fig. 4 is an enlarged sectional elevation of the pasting mechanism, by which the plastic material is pressed into the openings of the foraminous conveyer apron;

Fig. 5 is an enlarged sectional elevation illustrating the manner in which the apron girts are deposited on the movable supports;

Fig. 6 is an enlarged sectional elevation taken on the line 6—6, Fig. 1, and

Fig. 7 is an enlarged view of a detail of the invention.

The apparatus illustrated in the drawings comprises a casing 1, in one end of which, adjacent the bottom thereof, is rotatably mounted a transversely extending shaft 2. Adjacent the top of the casing 1, at a point inwardly removed from the shaft 2, is a pair of short shafts 3, 3, which extend transversely of the casing, in axial alignment with each other.

Extending at an angle with respect to the base of the casing 1, and inclined from a point substantially adjacent the shaft 2 to a point substantially adjacent the short shafts 3, 3, and on each of the oppositely disposed sides of the casing 1, is an inclined support 4.

On each of the guides 4, 4, is adapted to ride one portion of a drive chain 5. The drive chains 5, 5 pass respectively around sprockets 6, 6 disposed at opposite ends of the shaft 2, around sprockets 7, 7 mounted respectively on the short shafts 3, 3, and around idler sprockets 8, 8, 110

and 9, 9, rotatably mounted in the casing 1 adjacent the opposite sides thereof respectively.

Intermediate the drive chains 5, 5 is located an endless foraminous conveyer 10. The conveyer 10 is provided with uniformly spaced girts 11, 11, each girt having projections 12, 12 extending laterally from the side edges of the apron 10. The projections 12, 12 when in one part of the apparatus are adapted to rest on the drive chains 5, 5, and to be engaged by driving lugs 13, 13 carried by or formed on the drive chains 5, 5.

When the drive chains 5, 5 are actuated, the conveyer apron 10 will be drawn upward along the inclined guides 4, 4, the apron 10 passing around a roller 14 mounted on the shaft 2 at the lower ends of the inclined guides 4, 4. The apron, after passing around the roller 14, will be drawn through a suitable pasting mechanism 15, which is positioned along the inclined guides 4 and extends across the apron between the said guides 4, 4 at a point intermediate the shafts 2 and 3, and preferably adjacent the lower ends of the guides 4, 4 as shown in Fig. 1.

Actuation of the drive chains 5, 5 causes one pair of lugs 13, 13 on the chains 5, 5 respectively to engage the opposite ends of one of the girts 11 of the conveyer apron 10, thereby moving the said girt upwardly along the inclined guides 4, 4 and pulling the said conveyer apron 10 through the pasting mechanism 15, by which the plastic material is pressed into the openings into the said apron, as above noted. The engaged girt 11 continues to be carried upwardly along the guides 4, 4 and over the sprockets 7, 7 on the short shafts 3, 3, whereupon the projecting ends 12, 12 of the said girt will engage and pass downwardly along reverse inclined guides 16, 16, to the upper run of a pair of movable supporting chains 17, 17 which are disposed respectively at opposite sides of the casing 1.

About the time the first said girt reaches the sprockets 7, 7, the next successive girt 11 of the apron 10 is emerging from the delivery end of the pasting mechanism 15 and is being carried upwardly along the inclined guides 4, 4 by another pair of driving lugs 13, 13 on the chains 5, 5. The portion of the conveyer apron 10 disposed between the two girts 11, 11 begins to sag intermediate the two girts, as soon as the leading girt of the pair is deposited on the relatively slow moving supports 17, 17, the trailing girt 11 of the pair being carried by the chains 5, 5 which are moving at a considerably greater rate of speed than the leading girt now carried on the slow moving supports 17, 17, whereby the formation of a loop 10^a begins, a bend 10^b being formed in the section of the apron substantially equidistant from and between the two girts, this bend becoming progressively sharper as the said trailing girt is moved upwardly along the guides 4, 4 and approaches the sprockets 7, 7 on the shafts 3, 3, the loop attaining its final state of flexing, as illustrated at 10^c, when the said trailing girt moves downwardly along the reverse inclined guides 16, 16 onto the movable supports 17, 17.

The supports 17, 17 moving at a relatively low rate of speed with respect to the rate of speed of travel of the apron section 10, determines the spacing of the girts 11, 11 on the movable supports 17, 17 and consequently the degree of sharpness in the bend of each loop formed.

The movable supports or chains 17, 17, as

shown in Fig. 6, are provided with rollers 18, 18 which ride on supporting rails 19, 19, secured to the framework at opposite sides of the casing 1, the chains 17, 17 respectively passing around sprocket wheels 20, 20, located immediately adjacent the sprockets 7 and 8, and around sprocket wheels 21, 21 rotatably mounted in the casing at a point removed from the sprockets 20, 20, as clearly illustrated in Fig. 1.

As the upper runs of the supporting chains 17, 17 move in the direction of the arrow shown in Fig. 1, the looped conveyer is advanced through the casing 1 and is therein subjected to any desired form of treatment, such as drying, etc., after which the portion of the conveyer apron 10 disposed adjacent the sprockets 21 passes around a roller 25 mounted on a transversely extending shaft 26, the roller traveling at the peripheral speed substantially equal to the speed of travel of the drive chains 5, 5, whereby the conveyer apron is drawn out of the loops, one after another, and the straightened conveyer apron is directed between a pair of substantially vertically extending pair of guides 27, 27, respectively located at the oppositely disposed edges of the conveyer apron.

The conveyer apron is guided by the guides 27, 27 in a downward direction and while in such position is subjected to a beating operation performed by a beater 28 which beats the treated material out of the conveyer, the said material falling into a hopper 30 disposed adjacent the bottom of the casing 1, the said hopper being provided with a feed screw 31 which carries the said material outside the casing.

Adjacent the bottom of the casing the conveyer apron 10 passes around a roller 32, mounted on a transversely extending shaft 33, and onto a horizontally disposed platform 34, along which the said conveyer apron passes throughout substantially the full length of the casing, which brings the said conveyer and the girts 11 thereof under the lower runs 5^a, 5^a, of the drive chains 5, 5, intermediate the sprockets 9, 9, and the sprockets 6, 6 which are carried by the shaft 2 at the front end of the apparatus.

The travel of the conveyer 10 and that of the drive chains 5, 5 are so synchronized that as each girt 11 arrives at a point under the sprockets 9, 9 a pair of drive lugs 13, 13 on the drive chains 5, 5 will also reach and pass around the sprockets 9, 9 and engage the girt 11 which at that time is disposed under the sprockets 9, 9, whereupon the continued operation of the drive chains 5, 5 will move the conveyer apron 10 along the horizontal platform 34 and around the roller 14 on the shaft 2, as previously described.

From the above description, it will be obvious that after the conveyer apron 10 is loaded with the material to be treated, the said apron is subjected to but one gentle flexing before undergoing treatment in the casing 1, consequently the tendency of the material to be loosened in the conveyer apron is reduced to a minimum. After undergoing treatment, flexing of the apron is not objectionable as it has the tendency to break the material out of the apron.

The body of the apron 10 is preferably constructed in a manner similar to the apron disclosed in the co-pending application of Alpheus O. Hurxthal, Serial No. 305,589, filed September 12, 1928, which matured into Patent No. 1,772,423, the purpose of which is to remove the dried material from the apron by a relative flex-

ing of the apron elements. The removal of a portion of the material by the flexing of the apron reduces the necessity for severe beating of the apron, therefore, the beating produced by 5 the beater 28 is reduced to a very light tapping thereof.

While I have described my invention in connection with a foraminous conveyer apron in which the material-carrying openings or pockets 10 extend completely through the conveyer apron from one face to the opposite face thereof, it will be quite obvious to one familiar with the mechanical arts that the principles of the invention are applicable to any type of flexible 15 conveyer apron adapted to be suspended in loops.

I claim:

1. In an apparatus for treating plastic materials, the combination of a foraminous conveyer 20 having spaced projections along the side edges thereof, an inclined guide adjacent each side of the conveyer for supporting said projections, a pasting device adjacent the lower end of the inclined guides, supports for said projections adjacent the upper ends of said inclined guides, means for advancing the projections successively along the inclined guides to pull the conveyer taut between successively spaced girts and 25 between the upper supports and the pasting device, means for transferring the projections from the inclined guides to the said upper supports whereby the taut portions of the conveyer will be folded intermediate said girts to form the conveyer into loops between the pasting device and the upper supports and whereby the said loops will be supported solely by the said upper supports, means for advancing the loops along said upper supports, and means for drawing 30 the conveyer out of said loops at the opposite end of said upper supports.

2. In an apparatus for treating plastic materials, the combination of a foraminous conveyer having spaced projections along the side edges thereof, an inclined guide adjacent each side of the conveyer for supporting said projections, a pasting device adjacent the lower end of the inclined guides, supports for said projections adjacent the upper ends of said inclined guides, means for advancing the projections successively along the inclined guides to pull the conveyer taut between successively spaced girts and 45 between the upper supports and the pasting device, means for transferring the projections from the inclined guides to the said upper supports whereby the taut portions of the conveyer will be folded intermediate said girts to form the conveyer into loops between the pasting device and the upper supports and whereby the said loops will be supported solely by the said upper supports, means for advancing the loops along said upper supports, and means for drawing 50 the conveyer out of said loops at the opposite end of said upper supports, and means for returning the conveyer to the lower ends of the inclined guides for reloading by the pasting device.

3. In an apparatus for treating plastic materials, the combination of a foraminous conveyer 70 having spaced projections along the side edges thereof, an inclined guide adjacent each side of the conveyer for supporting said projections, a pasting device adjacent the lower end of the inclined guides, supports for said projections adjacent the upper ends of said inclined guides, means for advancing the projections successive-

ly along the inclined guides to pull the conveyer taut between successively spaced girts and between the upper supports and the pasting device, means for transferring the projections from the inclined guides to the said upper supports whereby the taut portions of the conveyer will be folded intermediate said girts to form the conveyer into loops between the pasting device and the upper supports and whereby the said loops will be supported solely by the said upper supports, means for advancing the loops along said upper supports, means for drawing the conveyer out of said loops at the opposite end of said upper supports, means for removing the material from the conveyer belt, and means for returning the conveyer to the lower ends of the inclined guides for reloading by the pasting device. 80

4. In an apparatus for treating plastic materials, the combination of an endless foraminous conveyer, transversely extending girts disposed at spaced intervals along said conveyer and having ends projecting beyond the side edges thereof, an inclined guide adjacent each side of said conveyer for supporting the projecting ends of said girts, a pasting device adjacent the lower ends of the inclined guides, supports for the girts at the upper ends of said inclined guides, drive chains movable parallel to said inclined guides and adapted to engage the projecting ends of said girts to advance said girts along said inclined guides to pull the conveyer taut between the pasting device and the upper support and to deliver the girts successively to the said upper supports, whereby the said taut portions of the conveyer will be successively formed into loops between the pasting device and the upper supports. 90

5. In an apparatus for treating plastic materials, the combination of an endless foraminous conveyer, transversely extending girts disposed at spaced intervals along said conveyer and having ends projecting beyond the side edges thereof, an inclined guide adjacent each side of said conveyer for supporting the projecting ends of said girts, a pasting device adjacent the lower ends of the inclined guides, supports for the girts at the upper ends of said inclined guides, drive chains movable parallel to said inclined guides and adapted to engage the projecting ends of said girts to advance said girts along said inclined guides to pull the conveyer taut between the pasting device and the upper supports and to deliver the girts successively to the said upper supports, whereby the said taut portions of the conveyer will be successively formed into loops between the pasting device and the upper supports, means for drawing the conveyer out of said loops, said conveyer returning to the lower ends of said inclined guides in a plane apart from the loops, means effecting disengagement of the drive chains from the girts adjacent the upper ends of the inclined guides, and means for effecting reengagement of the drive chains with said girts in the said return plane of the conveyer. 100

6. In an apparatus for treating plastic materials, the combination of an endless foraminous conveyer, transversely extending girts disposed at spaced intervals along said conveyer and having ends projecting beyond the side edges thereof, an inclined guide adjacent each side of said conveyer for supporting the projecting ends of said girts, a pasting device adjacent the lower 110

ends of the inclined guides, supports for the girts at the upper ends of said inclined guides, drive chains movable parallel to said inclined guides and adapted to engage the projecting ends of said girts to advance said girts along said inclined guides to pull the conveyer taut between the pasting and to deliver the girts successively to the said upper supports, whereby the said taut portions of the conveyer will be successively formed into loops between the pasting device and the upper supports, means drawing the conveyer out of said loops, said conveyer returning to the lower ends of the inclined guides in a plane disposed below the loops, means effecting disengagement of the drive chains from the girts adjacent the upper ends of said inclined guides, means effecting reengagement of the drive chains with the girts in the said return plane of the girts.

7. In an apparatus for treating plastic materials, the combination of an endless foraminous conveyer, transversely extending girts disposed at spaced intervals along said conveyer and having ends projecting beyond the side edges thereof, an inclined guide adjacent each side of said conveyer for supporting the projecting ends of said girts, a pasting device adjacent the lower ends of the inclined guides, supports for the girts at the upper ends of said inclined guides, drive chains movable parallel to said inclined guides and adapted to engage the projecting ends of said girts to advance said girts along said inclined guides to pull the conveyer taut between the pasting and the upper supports and to deliver the girts successively to the said upper supports, whereby the said taut portions of the conveyer will be successively formed into loops between the pasting device and the upper supports, means drawing the conveyer out of said loops, said conveyer returning to the lower ends of the inclined guides in a plane disposed below the loops, means effecting disengagement of the drive chains from the girts adjacent the upper ends of said inclined guides, and means effecting reengagement of the drive chains with the girts in the said return plane of the girts, said means comprising sprockets adjacent the upper ends of the inclined guides and sprockets adjacent the return plane of the conveyer around which the drive chains pass.

8. In an apparatus for treating plastic materials, the combination of an endless foraminous conveyer, transversely extending girts disposed at spaced intervals along said conveyer and having ends projecting beyond the side edges thereof, an inclined guide adjacent each side of said conveyer for supporting the projecting ends of said girts, a pasting device adjacent the lower ends of the inclined guides, supports for the girts at the upper ends of said inclined guides, drive chains movable parallel to said inclined guides and adapted to engage the projecting

ends of said girts to advance said girts along said inclined guides to pull the conveyer taut between the pasting device and the upper supports and to deliver the girts successively to the said upper supports, whereby the said taut portions of the conveyer will be successively formed into loops between the pasting device and the upper supports, means drawing the conveyer out of said loops, said conveyer returning to the lower ends of the inclined guides in a plane disposed below the loops, means effecting disengagement of the drive chains from the girts adjacent the upper ends of said inclined guides, means effecting reengagement of the drive chains with the girts in the said return plane of the girts, said means comprising sprockets adjacent the upper ends of the inclined guides and sprockets adjacent the return plane of the conveyer around which the drive chains pass, and sprockets located in the angle formed between the inclined guides and the return plane of the conveyer for transferring the conveyer from the return plane to the plane of the inclined guides.

9. In an apparatus for treating plastic materials, the combination of an endless foraminous conveyer, transversely extending girts disposed at spaced intervals along said conveyer and having ends projecting beyond the side edges thereof, an inclined guide adjacent each side of said conveyer for supporting the projecting ends of said girts, a pasting device adjacent the lower ends of the inclined guides, supports for the girts at the upper ends of said inclined guides, drive chains movable parallel to said inclined guides and adapted to engage the projecting ends of said girts to advance said girts along said inclined guides to pull the conveyer taut between the pasting device and the upper supports and to deliver the girts successively to the said upper supports, whereby the said taut portions of the conveyer will be successively formed into loops between the pasting device and the upper supports, means drawing the conveyer out of said loops, said conveyer returning to the lower ends of the inclined guides in a plane disposed below the loops, means effecting disengagement of the drive chains from the girts adjacent the upper ends of said inclined guides, means effecting reengagement of the drive chains with the girts in the said return plane of the girts, said means comprising sprockets adjacent the upper ends of the inclined guides and sprockets adjacent the return plane of the conveyer around which the drive chains pass, and sprockets located in the angle formed between the inclined guides and the return plane of the conveyer for transferring the conveyer from the return plane to the plane of the inclined guides, and a roll disposed between the last said sprockets around which the conveyer passes.

PHILIP W. BUR.
